Des. 208,058
Patented July 11, 1967

208,058

GOLF CLUB HEAD

Frank L. Johnston, 3157 Chicago Ave.,
Riverside, Calif. 92507

Filed Dec. 13, 1965, Ser. No. 154

Term of patent 14 years

(Cl. D34—5)

FIG. 2

FIG. 1

FIG. 3

I claim:

The ornamental design for golf club head, substantially as shown.
